UNITED STATES PATENT OFFICE.

JOHN M. HUFFER, OF KANSAS CITY, MISSOURI.

DESIGN FOR A SMOKER'S SET.

SPECIFICATION forming part of Design No. 36,903, dated May 3, 1904.

Application filed March 3, 1904. Serial No. 196,461. Term of patent 3½ years.

To all whom it may concern:

Be it known that I, JOHN M. HUFFER, a citizen of the United States, residing at Kansas City, in the county of Jackson and State of Missouri, have invented a new, original, and ornamental Design for a Smoker's Set, of which the following is a specification.

The figure shows the design of the smoker's set in perspective.

What I claim as new, and desire to secure by Letters Patent, is—

The ornamental design for smoker's set, as shown.

JOHN M. HUFFER.
